Patented Apr. 23, 1968

210,823

CHAIR FOR USE IN A SHOWER BATH

Lucille Nelson, 3011 Frances Ave.,
La Crescenta, Calif. 91041

Filed Mar. 27, 1967, Ser. No. 6,398

Term of patent 14 years

(Cl. D15—1)

FIG. 1 is a front perspective view of a chair for use in a shower bath showing my new design,

FIG. 2 is a side elevational view as viewed from the left hand side of FIG. 1,

FIG. 3 is a rear elevational view, and

FIG. 4 is a bottom plan view.

I claim:

The ornamental design for a chair for use in a shower bath, substantially as shown.
